UNITED STATES PATENT OFFICE

LELIA MARSHALL, OF BUFFALO, NEW YORK

NECKTIE SUPPORTER

Application filed August 6, 1930. Serial No. 473,398.

This invention relates to a necktie supporter and has for its primary object to provide, in a manner as hereinafter set forth, a device of this character embodying the novel 5 construction and arrangement of parts, whereby the necktie will be maintained in proper position relative to the collar when worn.

Other objects of the invention are to provide a necktie supporter of the character described, which will be simple in construction, strong, durable, highly efficient in its use and which may be manufactured at a low cost.

15 All of the foregoing and still further objects and advantages of the invention may become apparent from a study of the following specification, taken in connection with the accompanying drawings, wherein like characters of reference designate corresponding parts throughout the several views, and wherein:

Figure 1 is a view in front elevation showing the support constructed in accordance 25 with this invention mounted in position.

Figure 2 is a view in cross section through a neck band, of a shirt, showing the support constructed in accordance with this invention, mounted thereon, said support being 30 shown principally in side elevation and partly in section.

Figure 3 is a view in elevation of the support per se.

Figure 4 is a perspective view of a slightly 35 modified form of the support.

Referring to the drawings in detail, it will be seen that the reference numerals 1 and 2 designate the overlapping opposite end portions of the neck band of a shirt, having the 40 collar 3 thereon, the ends of said neck band being secured together in the usual manner by the conventional collar button 4. A necktie of the four-in-hand type is designated by the reference numeral 5.

45 The supporter constituting one embodiment of the present invention comprises an elastic strap 6, and an inelastic strap 7, said straps 6 and 7 being folded upon themselves and having their opposite ends stitched together as at 8, in a manner to provide oppo-

sitely extending loops. The fold of the inelastic strap 7 have formed therein adjacent the fold line of said strap 7, a longitudinally extending eye 8, through which the shank of the collar button 4 is embedded. 55

In use, the loop 7 is folded, over the overlapping end portions 1 and 2 of the neck band of the shirt, in the manner clearly illustrated in Figure 2 of the drawings and the eye 8 is aligned with the button holes in the neck band. The collar button 4 is then inserted and it will then be noted that the loop 7 is thus secured between the inner side of the neck band and the comparatively large disc on the inner end of the collar button. It will 60 be seen that the elastic loop 6 depends between the wings of the collar 3, and a finger or suitable implement is inserted through the loop 6 and said loop is stretched after which the necktie 5 is tied on said loop. It 65 will thus be seen that the loop 6 extends through the knot in the necktie. The loop 6 is then released and in returning to its normal unstretched position, the necktie will be moved upwardly and engaged tightly in 70 position against the collar. 75

In the slightly modified form of the invention, illustrated in Figure 4 of the drawings, an elastic strip is folded upon itself to provide the loop 10, the opposite ends of which 80 may be stitched or otherwise secured together and through which a suitable flexible inelastic loop in the form of a cord or other strand of material 11 is inserted.

The loop 11 is comparatively short and is 85 adapted to be slipped over the head on the forward or outer end of the collar button and suspended from the shank of said collar button forwardly of the neck band of the shirt. The manner of using the device illustrated in 90 Figure 4 is the same as the device illustrated in Figures 1, 2, and 3, and need not be repeated here.

It is believed that the many advantages of 95 a necktie supporter constructed in accordance with this invention will be readily understood and although the preferred embodiment of the invention is as illustrated and described, it is to be understood that changes in the details of construction may be had, 100

which will fall within the scope of the invention as claimed.

What is claimed is:

1. A necktie supporter of the character described comprising, in combination, a flexible loop of inelastic material and a flexible loop of elastic material, said loops connected together at one end, the inelastic loop having a buttonhole adjacent its free end for connection with a collar button.
2. A necktie supporter of the character described comprising, in combination, a pair of flat, flexible strips, one of said strips being formed of elastic material, the other of the strips being formed of inelastic material, said strips being folded upon themselves transversely at their middle and having their ends stitched together in a manner to provide connected loops, the folds of the free end portion of the inelastic loop having aligned buttonholes therein for receiving a collar button.

In testimony whereof I affix my signature.
LELIA MARSHALL.
